Application July 21, 1948, Serial No. 39,936

In Great Britain July 22, 1947

4 Claims. (Cl. 315—323)

1

This invention relates to electronic counting devices using gaseous discharge tubes.

In my copending applications bearing Serial Numbers 777,815, 777,816, respectively, both filed October 3, 1947, I have described counting circuits using gaseous discharge tubes where the electrodes are arranged so as to provide a number of discharge gaps.

In one application of such a device, a potential is applied between the two electrodes of each gap, and the anode electrodes of the gaps may be connected together inside or outside the tube, likewise the cathodes.

It is arranged that the said potential, which may be supplied from a battery, is insufficient to initiate a discharge across any gap, but is sufficient to maintain a discharge once begun.

Pulses of the same polarity as the battery are applied across all the gaps in common and the combined potential of the battery and the pulse will fire one gap only (called the "starting gap") when the gas in the tube is not ionised.

A first pulse applied to the tube will fire the starting gap which will continue to discharge owing to the battery potential. A second pulse will be able to fire another gap adjoining the starting gap owing to the migration of the ionisation of the gas atmosphere in the tube, from the starting gap to the adjoining gap. A third pulse will fire yet another gap due to the migration of gas ionisation to this gap from the adjoining gap secondly fired.

The sequence will continue till all the gaps are fired from successive pulses and arrangements are made on the firing of the last gap, to procure a voltage drop which extinguishes all the discharges.

It is a feature of these devices that if it is desired to operate the tube in a series of gap sequences, the time between pulses must be sufficient for ionisation to collapse in the absence of discharges in the tube, so that after all gaps have been fired and extinguished together, the next pulse will only operate the starting gap. The starting gap and no other gap will then be fired from the next pulse after the extinguishment of all the gaps. If ionisation was still present to any substantial degree at the time of the next pulse after extinguishment of the discharges, all the gaps would be in a condition to fire when that next pulse arrived and not just the starting gap.

The pulse repetition rate at which such tubes can function is therefore limited, unless special means are provided as described in my said co-

2

pending application Serial No. 777,815 to insert an interval equal to the de-ionising time between the final pulse of one sequence and the starting pulse of the next sequence.

5 It is proposed to provide a counting device, using a gaseous discharge tube where there is no battery potential applied between pulses to maintain the discharge in gaps once they have been fired and in which the pulse repetition rate 10 which may be applied, is raised by the reduction of de-ionising time due to the complete extinguishment of all discharges between pulses as compared with the time required for de-ionisation when the discharges are maintained 15 by a battery between the pulses of a train.

The invention consists of a circuit arrangement for a cold cathode gas discharge tube having three or more separate anode-cathode discharge gaps so arranged that ionisation of the 20 gas in the vicinity of a gap due to a discharge across that gap lowers the potential needed to fire an adjacent unfired gap, the tube being so constructed and the gaps so connected and interconnected that when a series of pulses are 25 applied to the gaps in parallel, the gaps will fire in turn, the last gap at least, firing alone.

Certain embodiments of the invention will now be described in relation to the accompanying drawings in which—

30 Fig. 1 is a circuit diagram of a counting device using a cold cathode gas discharge tube having several discharge gaps in which the gaps are fired successively from recurrent pulses, each gap re-firing on each pulse of a pulse train once it 35 has been initially fired, there being no "maintaining" battery.

Fig. 2 is a circuit diagram of a counting device using a cold cathode gas discharge tube having several discharge gaps in which the gaps are fired successively from recurrent pulses, each gap firing once only during each pulse train, there being no maintaining battery, due to the action of an additional cathode as compared with the tube illustrated in Fig. 1, co-operating 40 with the anode.

Fig. 3 is a circuit diagram of counting device employing a cold cathode gas discharge tube having a large number of gaps which can be used instead of the circuit of Fig. 2 where it is required to count pulses to a large radix, having an additional cathode as in the tube illustrated in Fig. 2 but co-operating with a second anode.

Figs. 4 and 5 are diagrammatic plan and elevation respectively of a method of construction

3 of a tube of the type used in the device illustrated in Fig. 3.

In Fig. 1 is a gas tube, with common anode (strip or wire) 2 connected through resistor 3 to ground, 5 is an indented cathode with equal spacings between points, and with equal gaps to the anode except at a starting gap 4, which is slightly shorter. 5 is connected to ground through resistor 6. 7 is an extra cathode the same distance from the anode as are the points of the indentation of cathode 5 except a gap 4, and with the same spacing from the last point on 5 as the distances of the points on 5, one from another. 8 is a third cathode consisting of a small plate, also at the same distance from the anode as the points on 5 (except 4), and with its left-hand edge at the same spacing from 7 as the inter-point spacing on 5. 7 is connected to ground through a resistor 9 shunted by a small condenser 10. 8 is connected to ground via a resistor 11 and one winding (hereinafter called the "primary winding") of a pulse transformer 12.

Resistor 11 and the primary winding of 12 are shunted by a small condenser 13 (only a few p.f.) and the primary winding of 12 is shunted by a rectifier 14. The other winding of 12, (hereinafter called the "secondary winding"), shunted by impedance 15, gives output pulses at terminals 16.

A rectifier 17, in series with battery 18 is connected between anode 2 and cathode 5.

In the following description, in describing the discharges which take place between the cathodes of a tube and its anode 2, or anodes, the expression "fire" will be used to indicate the inception of a discharge and when one of the said cathodes or a part, point or indentation thereof is said to be firing or discharging it will indicate that a discharge is initiated or is taking place between such cathodes, part, point or indentation and the anode or anodes of the tube, the reference to the anode or anodes being omitted for the sake of brevity where this can be done without ambiguity.

The input pulses to be counted are applied with negative polarity at terminal 19, and thence pass to cathode 8 via a blocking condenser 20. Terminal 19 is also connected to cathode 5 via a small delay network 22, and condenser 21, and to cathode 7 via network 22, resistance 6 and the condenser-resistor combination 10, 9. 22 may consist for example, of inductances 23, 24 with condensers 25, 26, its delay time is greater than the build-up time of the leading edge of the input pulses, but less than the pulse duration. The input pulse amplitude is such that in the absence of ionisation of the gas in the tube, only the shorter gap 4 will strike.

The rectifier 14 connected across the primary winding of transformer 12 shunts the input pulses from terminal 19 (which would otherwise have to pass through this winding on their way to cathode 8), and prevents them from reaching output terminals 16.

Let a first input pulse be applied at 19. Gap 4 will fire and the discharge will be maintained during the pulse duration and on cessation of the pulse the discharge through 4 will immediately cease, as there is no maintaining battery. If the next pulse arrives before the ionisation of the gas in gap 4 has had time to die away (e. g. within several microsecs., or less), the next pulse at 19 will fire the cathode point adjacent to 4 (the constants being so arranged), as well

as re-firing 4 since the ionisation of the gas will have spread from gap 4 to this adjoining gap. Both discharges will then go out when this second pulse ceases. The third pulse will fire the first three points from the left and so on, until all the indentations on 5 fire at once, on some later pulse.

It is to stabilise the pulse peak voltage across cathode 5 and anode 2, which tends to vary as the number of simultaneously discharging gaps is changing, that the battery 18 and the rectifier 17 in series with it, are connected between anode 2 and cathode 5.

The total voltage applied across rectifier 17 is determined by the voltage between anode 2 and cathode 5, superimposed upon the voltage of battery 18 the latter being connected so as to oppose the voltage derived from the pulses.

The potential of battery 18 is adjusted so that the peak of the input pulse just passes current through 17 when all the points on 5 fire together, and rectifier 17 is connected in the direction such that when less than the full number of points on 5 fire a greater current will pass through it.

When fewer gaps are discharging, therefore, the rectifier 17, being in a conducting condition, will be virtually in shunt across anode 2 and cathode 5 so as to pass current at these times, which, together with the current flowing through the parallel path between anode 2 and cathode 5, will equal approximately the current flowing between anode and cathode when all gaps are discharging.

All this current passes through resistances 3 and 6, thus limiting the input peak volts between 2 and 5 to a substantially constant value thereby preventing the variable voltage drop which would take place but for the insertion of rectifier 17 and battery 18, as different numbers of points on 5 fired, on successive pulses.

The degree of voltage stabilisation given by rectifier 17 is such that it will maintain a relatively stable voltage over the range of currents passed through the tube between the condition when no discharge is taking place on the one hand and when all the points of cathode 5 are discharging on the other hand. At the latter point the rectifier becomes non-conducting and further rises in current through the tube will cause a drop in the peak voltage of the pulses applied to the tube which will not be compensated by the rectifier 17.

When all the points on 5 have fired, the next pulse will fire 7, and also all the points of 5. The condenser 10 and the resistor 9 have values such that the current through 7 on its firing, charges 10 sufficient to prevent the next few pulses from re-firing 7. The time-constant of the combination 9-10 is several average pulse time spacings and not greater than the pulse train recurrence period, which may be 100 microseconds, for example.

The next pulse after that which fired 7, will fire cathode 8. This cathode however, is connected directly to the source of pulses via condenser 20 and terminal 19 whereas cathodes 5 and 7 are connected to 19 via the delay network 22.

The pulse will therefore reach 8 before it reaches cathodes 5 and 7, by an amount equal to the delay of delay network 22 which is greater than the time taken by the pulse to reach its peak amplitude but less than the pulse duration.

As 8 has a relatively large surface a current will tend to flow between 8 and 2 as the pulse

voltage builds up. This current, which flows through the common anode load 3 will lower the voltage at anode 2 at the time of the pulse peak and this will limit the current rise between cathode 8 and anode 2, an equilibrium being quickly reached at a point where the discharge across this gap is just maintained.

It is arranged that this equilibrium is reached before the delayed pulse reaches the other cathodes 5 and 7 and it is also arranged that the voltage of anode 2 at the equilibrium aforesaid, is insufficient for any of the points of cathode (even gap 4) to fire, and cathode 7 is prevented from firing in any event by virtue of the charge in condenser 10.

Cathode 8 has a time constant circuit consisting of a condenser 13 and a resistance 11, connected in the path along which the pulses reach cathode 8.

The next pulse cannot re-fire 8, on account of the charge collected on condenser 13 the time-constant of 11—13 being several pulse spacings.

With the exception of gap 4, the only cathode point now having enough residual ionisation for a re-fire to be possible is 7, next to 8 which has just been fired, the right-hand point on 5 being twice the distance from 8 as is cathode 7 and being substantially de-ionised since 7 has not fired on the last pulse. But 7 cannot re-fire because of the charge still remaining on 10. Therefore only the starting gap 4 will fire, and the sequence of events will start again. By the time that 7 or 8 are due to re-fire, the charges on 10 and 13 will have leaked away substantially to zero—so they fire as in the first sequence.

The fact that the anode-cathode voltage drops completely to zero between pulses speeds up the de-ionising time, as compared with devices where extinguishment is effected by a mere drop in volts (not down to zero) due to a surge of current through the last electrode to fire.

In devices using a tube and a battery which maintains the discharges between pulses, extinguishment of the discharges in the tube, after all its points have been fired, is achieved by a current surge which produces a voltage drop in a common load sufficient to lower the voltage to the point at which the discharges cannot be maintained, the last electrode, the firing of which causes this surge, must have a relatively large smooth surface and where the tube has a large number of gaps passing a large current when discharging, it may be difficult to design a last electrode, capable of passing a sufficiently larger current to produce the voltage drop necessary to extinguish the discharges. In the case of cathode 8, in this embodiment of the invention, the current surge need only be sufficient to cut the peak of the pulse below the voltage necessary to initiate a discharge across the points of cathode 5. Cathode 8 can therefore be relatively small and this is another advantage of this arrangement.

The counting function of the device is achieved by the delivery of a pulse through transformer 12 to terminals 15, every time cathode 8 fires, which is once in every pulse train.

The radix of the count is a number equal to the number of firing points on cathode 5 plus cathodes 7 and 8 as all these points strike once in the sequence of discharges in the tube, i.

In Fig. 2 a gas tube 27 has a common anode 28 consisting of a wire or strip, connected to ground through resistor 29. A cathode 31 with shorter gap 30 at one end, is an indented cathode as in Fig. 1. Cathodes 32 and 33 are of the same de-

sign as 7 and 8 respectively of Fig. 1. An extra cathode 34, consisting of a wire or strip, is either parallel to 28, or inclined to it at a slight angle so as to make the gap from 34 to 28, slightly bigger at the left hand end than at the right hand, 34 has a projecting point 36 at the right-hand end giving a somewhat shorter gap at 28 at this end than at other parts of the cathode 34. Cathode 31 is connected to ground via a resistance 41. 34 is connected to ground via resistance 35. 32 is connected to ground via resistance 37; and 33 is connected to ground via a resistance 39 and one winding of a pulse transformer 41 in series with resistance 39. Another winding of transformer 41 is terminated by impedance 42, and output pulses are obtained at terminals 43. 37 is shunted by small condenser 38, and resistance 39 in series with one winding of transformer 41 is shunted by condenser 40, as in Fig. 1. Positive input pulses are applied at terminal 44, and thence to anode 28 via a condenser 45.

The design and constants are such that an input pulse will always fire the gap between anode 28 and point 36 on cathode 34. A glow will then very rapidly spread along the surface of cathode 34, covering the entire length before the end of the duration of the pulse applied at 44. It is also arranged that the input pulses between 28 and 31 are insufficient to fire any point on cathode 31, notwithstanding the presence of the leading edge of the cathode glow on 34 spreading from right to left, except the short gap 30 on cathode 31. However, in the presence of the leading edge of the spreading glow on 34 combined with ionisation of the gas in any of the gaps between cathode 31 and anode 28 caused by immediately previous firing of an adjacent point on 31, the voltage at the times of the pulses is sufficient to cause the firing of any gap of 31, or cathode 32. Similarly plate 33 can only be fired by ionisation spreading from the immediately previous firing of 32, together with the presence of the leading edge of the glow spreading from right to left along 34. 34 may not be immediately above 28 as shown but may be placed in any position which will give the spacing from 28 above described; for instance, it may be placed so that the plane common to 34 and 28, is at right angles to the plane common to 28—31—32—33 and 28. To achieve the above result a tolerance of about $\pm 5\%$ in input pulse amplitude and of the same order in gap spacings from anode 28, of the points on 31 and cathodes 32 and 33, will in general be sufficient.

Let the first input pulse now be applied at 44. The gap between point 36 on cathode 34 and anode 28 will fire, and a glow will spread rapidly up the smooth surface of 34 from right to left. During the pulse the leading edge of the glow on 34 will have reached the shorter gap 30, of cathode 31 and 30 will then fire. 32, 33 and all other points than 30, on 31 will not fire, as there is no ionisation of the gas in them from adjacent gaps. On cessation of the pulse at 44 the discharges will extinguish. The next pulse will again fire 34, starting as before at its shorter gap 36. The glow on 34 spreading from right to left will now find that the first point on the line of the points on 31 that is capable of being fired is the gap from point 46 on 31 which is immediately to the right of 30—as this gap is the first, from right to left, in which the gas is sufficiently ionised for the pulse to be able to fire it. The ionisation is due to the recent discharge from point 30 which ionisation will persist between

pulses. This gap, 46 will fire before the leading edge of the glow on 34 has reached 30. As soon as 46 fires the voltage drop across the common cathode load 47 lowers the volts between 46 and 28 to a value sufficient to maintain the discharge from point 46 but insufficient to fire 30, which remains out. Similarly, the next pulse, after the extinguishing of 46 at the end of the previous pulse, will fire the adjoining gap 48, but no other—as 48 is the first sufficiently ionised gap to be reached by the glow on 34 spreading from right to left.

Successive pulses will similarly fire adjacent points, on 31 one at a time, from left to right, until all points on 31 have been fired. The next pulse will fire only 32—and the following pulse only 33. In each case the points of cathode 31 will not re-fire owing to the voltage drop in cathode load 47 on the firing of 32 and 33 respectively.

When 33 fires, 32 cannot re-fire, on account of the charge collected on 38 the action being similar to cathode 7 in Fig. 1. 33 itself cannot re-fire, because of the charge collected on 40 and all the long gaps between 28 and 31, are insufficiently ionised. Therefore on the arrival of the pulse following that which fired cathode 33, the shorter gap 30 only will fire again, as soon as the glow on 34 has spread to the left-hand end of 34. The sequence then repeats itself indefinitely. The time-constants of 37—38, and of 39—40 are greater than two input pulse time spacings and less than one period of the complete pulse train.

As only one point on cathode 31 can fire at a time, no measures are necessary to stabilize cathode-anode voltage.

If the input pulses are not strong enough alone to fire the cathodes, a battery may be added in series with resistor 29 and ground to assist the pulses. This battery must be insufficient to maintain any glow in the absence of an input pulse. This last addition, of course, slows down the deionising time somewhat, as the anode-cathode voltages no longer fall to zero between pulses.

The arrangement of Fig. 2 has the advantages of simplicity low power consumption, rapid operation and long tube life due to the short average time during which each cathode point (except 34) is discharging.

It has thus many of the advantages of the "memory" effect, which is described in another of my copending applications, bearing Serial No. 763,655, filed July 25, 1947.

In Figs. 3, 4 and 5 is shown a device which can be adapted to give the performance of the device illustrated in Fig. 2. A much larger number of gaps can be used with this device.

The dotted line of Fig. 3 encloses a diagram in perspective of the electrodes of a gas discharge tube for use in the device, consisting of a grid-like anode 49 having parallel longitudinal members joined to transverse end members, and a cathode 50, consisting of a wire or strip bent so as to pass to and fro above the anode 49 and having longitudinal members at right angles to the longitudinal members of anode 49, joined at alternate ends by blinds 51, 52, 53 and 54. Anode 49 and cathode 50 are in parallel planes separated by a distance suitable as the discharge gap of a gas discharge tube.

The end of 50 furthest from the leading-in connection 55 has a thickened portion reducing the gap 56 between it and the adjacent member

of 49 to a distance shorter than that between the planes of 49 and the remainder of 50.

At the crossing places between the longitudinal members of cathode 50 and anode 49 there is a series of discharge gaps 56, 57, 58, 59 and 60 along one longitudinal member of 50 and continuing, after bend 51, with further gaps 61 and 62, and so on till the final gap 63 near the leading out connection 55.

10 In a plane parallel to those of 49 and 50, is a cathode 64 similar in shape to 50 but preferably having somewhat longer longitudinal members, laterally displaced in relation to those of 50.

15 Another anode consisting of a flat plate 65 is in a plane parallel to the planes of the other electrodes described above.

The planes of electrodes 49, 50, 64, and 65 in that order, are preferably arranged side by side 20 or one above the other, and spaced apart so as to provide gap distances equivalent to those used in the tube of Fig. 2. For this purpose the gaps between 49 and 50, at the intersections are equivalent to the gaps between 31 and 28 of 25 Fig. 2 and the gaps between 64 and 65 are equivalent to the gaps between 34 and 28 in Fig. 2.

Any other arrangement of the electrodes giving these relative spacings could be used, for instance 49 could be placed below 50, 75 and 78 and not above them as shown in Fig. 3.

At the end of cathode 64 nearest to the leading out connection 66 is a projection 67 pointing towards anode 65, and making a smaller gap at this point, between 64 and 65, than at other parts of these two electrodes.

40 Negative pulses, applied to terminal 68 are conveyed to cathode 50 via condenser 69, resistance 70 and lead 55. They are of insufficient amplitude by themselves to cause a discharge between 50 and 49 (the latter being connected to earth via a resistance 71).

The same pulses are also applied to cathode 45 64 via condenser 72, resistance 73 and lead 66, where they cause a discharge from point 67 to anode plate 65 which rapidly spreads in the form of a glow between cathode 64 and anode 65, following the course of the former from point 67 towards the other end of 64.

50 It is arranged that the size of gap 56 is such that the glow between 64 and 65, is sufficient to cause a discharge across this gap in the presence of a pulse together with the leading edge of the glow from cathode 64 when it reaches the vicinity of gap 56.

55 The circuits constants and tube design are such that the glow between 64 and 65 reaches the end of 64 after about half the pulse duration.

A discharge now takes place across gap 56 and 60 the glow spreads during the remainder of the pulse along cathode 50 in the direction of gap 57 causing ionisation to spread rapidly to that gap.

65 It might be thought that the gap 74 between the same longitudinal member of 49 and the adjoining longitudinal member 50 would be equally ionised but this is not so owing to the more rapid spread of ionisation when accompanied by the cathode glow, which spreads along a smooth cathode surface whereas the ionisation spread from 56 to 74 must cross an air gap.

On cessation of the pulse the discharge in 56 collapses and the next pulse repeats the process starting with the firing of point 67 to anode 65 75 and the spread of the glow along 64.

It will be clear of course that the spreading glow along 64 passes near to the various discharge gaps at the crossing places between 49 and 50 in turn in reverse order. On reaching gap 57, between 49 and 50, next after gap 56, there is enough ionisation to cause this gap to fire.

The gaps between 49 and 50, except 56, are of a size such that they will fire in the presence of the pulse, together with the leading edge of the glow between 64 and 65, and of residual ionisation at a level produced by a discharge in a gap adjacent along one of the longitudinal members of 50, that is to say, where the spread of ionisation is accelerated by the spreading cathode glow along 50 during a discharge. The gap is adjusted however so that the ionisation which can reach a gap across an air space equal to the gap spacing between connective gaps along 49, is insufficient to cause a discharge. Hence gap 74 will not fire from this second pulse, when the glow from 64 reaches it.

When gap 57 has fired, the glow from 64 will pass on to gap 56 but this gap cannot fire owing to the voltage drop in the common resistance 70 due to the discharge in gap 57.

The process will be repeated from successive pulses, each pulse firing a further consecutive gap, and gaps firing once only.

When gap 60 is reached, the cathode glow will spread round bend 51, assisted by the proximity of the end longitudinal member of 49, and when the next pulse arrives, gap 61 on the next longitudinal member of 50, will fire. Gap 61 will receive some ionisation direct, across the air gap between it and gap 60, and will be more ionised than gap 62.

The distance round bend 51, between gaps 60 and 61 may therefore be greater than that between adjacent gaps along one of the longitudinal members of 50, and still permit adequate ionisation of gap 61 for it to fire from the next pulse.

The discharges proceed along the full length of 50 till the last gap 63 is reached. Another cathode 75 is connected to the common resistance 70 via a time constant circuit consisting of resistance 76 and condenser 77. The cathode corresponds to and has the same function as cathode 32 in Fig. 2. It is adjacent to gap 63 and has the same gap distance from a convenient point of anode 49 as the gaps between 49 and 50 (except 56). It is also approximately as far from gap 63 as the lateral spacing between adjacent gaps between 49 and 50.

A further cathode 78 is placed near the cathode 75, being the same gap distance from anode 49 as is cathode 75 and being spaced from cathode 75 by the same distance as that between cathode 75 and gap 63.

Cathode 78 is of the same type and has the same functions as cathode 33, Fig. 2.

Cathodes 75 and 78 are also near enough to cathode 64 to be primed by the glow therefrom when ionised by an adjacent discharge.

When gap 63 has fired and extinguished, a further pulse will fire cathode 75 and yet another will fire cathode 78, as with cathodes 32 and 33 of Fig. 2, being prevented from firing from consecutive pulses by the time constant circuit 76 and 77 in the case of 75 and by the time constant circuit consisting of a resistance 79 and a condenser 80, in the case of cathode 78, 63 being prevented from re-firing from the same pulse as fires 75 and 78 by the voltage drop in common resistance 70.

The counting function of the device is fulfilled by the transformer 81, one winding of which is connected between cathode 78 and the common resistance 70, so that a pulse is developed across the terminals 82 and 83 connected to the other winding of 80, every time a discharge takes place from cathode 78.

The positions of cathodes 75 and 78 in Fig. 3 are diagrammatic, there being many possible arrangements for them, including that shown.

The function of the device described in relation to Fig. 3 operates in a similar manner to that of Fig. 2 but permits a larger number of gaps to be provided without unduly elongating the tube.

Figs. 4 and 5 show a plan and elevation of a possible practical construction of the electrodes of the tube illustrated within the dotted line rectangle in Fig. 3, the wires or strips composing cathodes 50 and 64 being supported on insulating pegs 85 attached to anode 65. In Figs. 4 and 5 corresponding elements are indicated by reference numerals corresponding to those in Fig. 3.

Here anode 49 is shown above the other electrodes, and the cathodes 75 and 78 are not shown since the purpose of Figs. 4 and 5 is principally to show the methods of mounting of electrodes 49, 50, 64 and 65.

It is thus seen that all the devices described in relation to the attached drawings possess the feature of having no battery potential applied to the electrodes between pulses, which is of advantage principally in the reduction of the deionising time due to the fall to zero of the anode-to-cathode potential between pulses rather than its reduction to a point above zero. This short deionising time enables the tube to resume sequential firing after a shorter recovery period and therefore enables a higher pulse repetition rate to be used.

The arrangements illustrated in Figs. 2, 3, 4 and 5 have the further advantage of having only one gap discharging at a time which obviates the need for voltage stabilising measures and increases the life of the tube owing to the reduced number of discharges across any gap.

What I claim is:

1. A device responsive to recurring pulses of electrical energy comprising a cold cathode gas discharge tube having a first electrode, a second electrode, said electrodes unevenly spaced from each other to define an extended discharge gap therebetween along which a discharge is adapted to spread upon application of successive pulses of a series, a plurality of auxiliary electrodes spaced substantially an equal distance from said first electrode and defining an array of sequentially firing auxiliary gaps therebetween, each having an ionization coupling with the extended discharge gap and an adjacent auxiliary gap, one of said auxiliary electrodes having a member defining a smaller gap with said first electrode than the array of auxiliary gaps, said member in proximity with that portion of said first electrode which is spaced farthest from said second electrode, successive of the auxiliary gaps adapted to be fired upon application of successive pulses of a series.

2. A device as claimed in claim 1 further comprising means for firing alone the sequentially firing gap distant farthest from said smaller gap, means for preventing re-firing of said first mentioned gap until all intervening auxiliary gaps 75 have re-fired and a load circuit coupled to said

11

electrodes responsive to the firing of said first named gap.

3. A device as claimed in claim 2 wherein said means for firing alone the last of the sequentially firing gaps defined by said electrodes comprises a time-constant circuit in series with the penultimate of the sequentially firing gaps defined by said electrodes, said circuit having a time-constant greater than the time spacing between recurring pulses applied to said tube.

10

12

4. A device as claimed in claim 3 wherein said means for preventing re-firing of said last sequentially firing gap until all intervening auxiliary gaps have re-fired comprises a time-constant circuit in series with said last sequentially firing gap, said circuit having a time-constant greater than the time spacing between recurring pulses applied to said tube.
